UNITED STATES PATENT OFFICE.

JOHN FRITSCHÉ, OF PHILADELPHIA, PENNSYLVANIA.

DISPENSING-CABINET.

1,367,033.

Specification of Letters Patent. Patented Feb. 1, 1921.

Application filed February 8, 1918. Serial No. 216,015.

To all whom it may concern:

Be it known that I, JOHN FRITSCHÉ, a citizen of the United States, residing in the city and county of Philadelphia, State of Pennsylvania, have invented a new and useful Dispensing-Cabinet, of which the following is a specification.

My present invention comprehends a novel construction and arrangement of a dispensing cabinet which is especially designed for the dispensing of towels for temporary use only and for the dispensing of a determined amount of soap, although, as will be apparent, it is not limited to such use and may be employed for the dispensing of other articles or material. The construction of the cabinet is such that clean towels are retained in a locked compartment and they can only be brought into a position accessible to the intended user or purchaser when a check or coin of the proper denomination has been deposited in the cabinet. The removal of a towel into a position accessible to the user effects the operation of the soap dispensing device to cause a determined amount of soap to be fed into a position accessible to the intending user.

My invention in its preferred form comprehends novel means to effect the removal of a towel from its compartment into a position accessible to the intending user, novel means for preventing the withdrawal of more than one towel at a time, novel means for preventing the insertion of a check or coin when the cabinet is empty, novel means for effecting the relocking of the mechanism by the removal of a towel from its compartment, a novel construction and arrangement of a soap dispensing device, and novel means for actuating it, a novel construction and arrangement of coin controlled operative mechanism, a novel construction and arrangement of a cabinet and novel means for retaining the unused towels and the used towels within the cabinet.

Other novel features of construction and advantage will hereinafter more clearly appear in the detailed description of my invention.

For the purpose of illustrating my invention, I have shown in the accompanying drawings typical embodiments of it which are at present preferred by me, since these embodiments will give in practice satisfactory and reliable results, although it is to be understood that the various instrumentalities

of which my invention consists can be variously arranged and organized and that my invention is not limited to the precise arrangement and organization of these instrumentalities as herein shown and described.

Figure 1 represents in perspective, a dispensing cabinet embodying my invention.

Fig. 2 represents a section on line 2—2 of Fig. 1.

Fig. 3 represents a sectional view, taken on the same line as that on which Fig. 2 is taken but having certain parts removed for the sake of clearness of illustration.

Fig. 4 represents a section on line 4—4 of Fig. 1.

Fig. 5 represents, in perspective, one of the articles to be dispensed, such as for example, a towel.

Fig. 6 represents a front elevation of the cabinet with the doors in open position.

Fig. 7 represents a rear elevation of a portion of one of the doors, with the towel retainer removed.

Fig. 8 represents in front elevation and on an enlarged scale a portion of the cabinet.

Fig. 9 represents a section on line 9—9 of Fig. 1.

Fig. 10 represents, in rear elevation, a portion of one of the doors and the means employed to effect the closing of the coin slot when the cabinet is empty.

Fig. 11 represents a front elevation of the coin controlling mechanism in detached position.

Fig. 12 represents a section on line 12—12 of Fig. 6.

Fig. 13 represents a top plan view, partly broken away, of the towel retainer.

Fig. 14 represents, in perspective and partly broken away, the lower end of the retainer in detached position.

Fig. 15 represents a section on line 15—15 of Fig. 16.

Fig. 16 represents, in sectional elevation, another embodiment of a soap dispensing device embodying my invention, which is adapted to dispense soap in powdered form.

Similar numerals of reference indicate corresponding parts.

Referring to the drawings:—

1 designates the casing of a dispensing cabinet embodying my invention. For convenience of illustration, I have shown it as being of substantially a rectangular con-

tour, although, as will be apparent, the contour of the casing may vary in accordance with conditions and requirements met with in practice. The cabinet is provided with an open front which is closed by means of the doors 2 and 3, respectively. At the upper left hand portion of the cabinet a partition 4 is provided which extends laterally from one side wall of the cabinet a desired distance and is then extended upwardly and secured to the rear wall of the cabinet in any desired manner and by such construction a chamber or compartment 5 is provided for the unused articles, such as for example, the clean towels which are to be dispensed. The partition 4 at its upper end, supports a roller 6.

7 designates a compartment having a bottom wall 8 and a side wall 9, the bottom wall being provided with a spout 10. 11 designates a table forming the top of a closed compartment 12 which may be utilized for any desired purpose. The table 11 is provided with a drainage opening 13 which is in alignment with the spout 10. 14 designates a guide bar which with the guide bar plate 15 carried by the door 2 forms a slot 16. The door 3 is also provided with an outwardly extending bar 17 which cooperates with the bar 15 to form a continuation of the slot 16, as will be best understood by reference to Fig. 1.

18 designates an article retainer which, as illustrated, is adapted to receive articles, such as towels, and at its upper end is provided with an extension 19 of reduced diameter, the end of which is secured in a bracket 20, see Fig. 6, by means of a set screw 21. This retainer extends laterally and then downwardly through the open-ended compartment 22, see Fig. 1, and it is then bent at an angle to extend into the compartment 23. Its lower end is of reduced diameter, as indicated at 24, and is secured to a bracket 25 carried by the door 2, it being understood that the bracket 20 is also carried by the door 2. When the towels come from the laundry, they are assembled on a carrier 26 which consists of a tube or sleeve through which the reduced end 19 of the towel retainer is adapted to extend and this sleeve is provided with a laterally extending stop arm 27 from which extends a rod 28 and to the forward end of the latter is pivoted a stop 29, see more particularly Fig. 13, which locks in a recess 30, see Fig. 6.

The extension 24 of the towel retainer is adapted to receive a tubular sleeve 30 having at its lower end a collar 31. The lower end 60 of the rod 18 is fixed to the bracket 25 by means of a set screw 32. The door 2 is provided with one or more key-controlled locks 33. The door 3 is provided with a spring lock 34. 35 designates the articles 65 to be dispensed, such as for example, towels,

which are provided with reinforced eyelets 36, and in order to effect their removal, I employ an article or towel remover 37 which consists of a casting or of a wire having at one end a grasping portion and at its opposite end a slot 38 in order that it may slide on the towel retainer.

Any desired type of check-controlled mechanism which is capable of operating in the manner hereinafter set forth may be employed but I have preferred to illustrate a novel construction and arrangement of check or coin-controlling mechanism, all of which is carried by the door 3. The door 3 is provided with a coin slot 39 which is of the proper dimension to receive a predetermined check or coin. This coin slot 39 communicates with the coin chute 40 and if the coin is of the proper dimension, it will pass through the coin chute 40, see Fig. 11, 8 and will come to rest between a cam 41 and a bar 42 which is slidably mounted in brackets 43 carried by a plate 44 which is secured to the door 3 in any desired manner. The cam 41 is carried by a rock shaft 45 which extends through the door 3 and is provided with a manually actuated handle 46.

47 designates a spring, one end of which is secured to a cam 41 while its opposite end is secured to a fixed portion of the plate 44 in order to maintain the cam 41 normally in the position seen in Fig. 11. The bar 42 has extending therefrom an arm 48 to which is connected one end of a spring 49, the other end of said spring being connected to one of the brackets 43. The bar 42 is provided with a shoulder or offset 50 which engages one of the brackets to retain a bifurcated end 51 across the slot 16 at certain times, see Fig. 9, and when the bar 42 is in the position seen in Fig. 9, it engages one end of the lever 52, see Fig. 9. This lever 52, as seen in Fig. 7, is pivoted to the door 2 as at 53 and is connected by means of a link 54 with a lever 55 which is pivoted at 56 to the door 2. The opposite end of the lever 55 has pivoted thereto a stop pin 57 which is guided in the door 2 so as to provide for its vertical movement. This stop pin 57 is located in proximity to a cam face 58 on the lever 52. The lever 52 is normally maintained in the position seen in Fig. 7 by means of a spring 59, one end of which is connected with the door 2 and the other end of which is connected to the lever 52.

The bar 42 is provided with a slot 60, into which extends one arm of a lever 61 which is pivotally carried by the plate 44, see Fig. 11, and the other end of said arm is weighted and of such length as to extend across the slot 16 when the bar 42 has been released. The bar 42 at one end is provided with a slot 62 which communicates with an aperture 63. The coin chute 40 is provided with a

fixed and with a movable side and one end of a lever 64 bears against the movable side and is connected with the rock shaft 45, so that if a check or coin is retained in the chute 40, owing to its being of improper dimension, it will be returned into a position accessible to the intending purchaser. When the movable side of the coin slot is open, the coin retained therein will drop into the return chute 65 and be delivered to the pocket 66 which opens through the front of the door 3.

The rock shaft 45 is connected by means of a lever 67 with a counter 68 which indicates the number of times the machine has been actuated. 69 designates a coin receptacle. The bar 42 controls the dispensing of the soap and the construction of the soap dispensing device will be best understood by reference to Fig. 12.

70 designates a container for the liquid soap which is provided with a discharge port 71 which is controlled by a valve 72, the stem of which is provided with a button 73. The discharge port 71 communicates with a measuring chamber 74 which is provided with a discharge port 75 which is controlled by means of a spring pressed valve 76.

In case it is desired to use soap in a solid form, such as for example, in the form of a powder, I preferably employ the construction seen in Figs. 15 and 16, from which it will be seen that the soap container 77 is provided with ports 78 which communicate with a measuring chamber 79.

80 designates an apertured slide valve having ports to be brought into register with the ports 78, and this valve is adapted to be actuated by a lever 81, one end of which extends through the apertured end of the bar 42. The slide valve 80 is provided with projections 82 which serve to loosen up the soap which is to be dispensed. The measuring chamber 79 is provided with ports 83 which are controlled by means of a spring pressed valve 84 having ports to register with the ports 83.

Referring now more particularly to Figs. 2, 3, 6 and 10, 85 designates a U-shaped bar, the free ends of which are pivotally connected within the cabinet and this bar normally rests on the article removing members 37. If, however, these have all been removed, this bar due to gravity and its own weight moves downwardly and bears against one end of a lever 86 pivotally carried by the door 2 and causes the opposite end 87 of the lever 86 to close the coin slot 39. The lever 86 is retained in its normal position by means of a spring 88, one end of which is connected with the lever 86, while its opposite end is connected to a fixed portion of the door 2.

The operation of the dispensing device

will now be apparent to those skilled in this art and is as follows:

Assuming that the dispensing device is to be used for the dispensing of towels and soap, the towels come from the laundry on the tubular sleeve 26 which is assembled on the reduced end 19 of the article retainer 18. The upper end of the retainer 18 is then fixed to the bracket 20 by means of the fastening device 21 and the lower end of the article retainer 18 which has thereon the tubular sleeve 30 is fixed to the bracket 25 by means of the fastening device 32. The towels in a folded condition as seen in Fig. 5, are strung on the tubular sleeve 26 and the stop arm 29 is moved into the position seen in dotted lines in Fig. 13. It will be understood that when the towels 35 are assembled on the sleeve 26 that the article removing device 37 is in rear of each towel, as will be understood by reference to Figs. 1 and 2.

Assuming now that the doors 2 and 3 are locked and that the towel compartment 5 has been filled with towels in the manner set forth, the intending purchaser places a check or coin into the coin slot 39. If the check or coin inserted is of the proper dimension, it passes through the slot 40 and if not it is retained in said slot. If it passes through the slot, it abuts against the inclined face of the cam 41 and bears against a shoulder on the bar 42, see Fig. 11. At this time, the bar 42, owing to the provision of its shoulder 50, is locked against one of the brackets 43 and the spring 49 is under tension. The intending purchaser or user now takes hold of the grasping handle 46 and rocks the shaft 45, thereby causing the cam 41 to move the coin upwardly against the shoulder on the bar 42 which cooperates with the coin. This causes one end of the bar 42 to be raised and as soon as its shoulder 50 is released from the bracket 43, the spring 49 causes the locking bar 42 to move longitudinally so that its end 51 moves out of the slot 16. This movement of the locking bar 42 permits the lever 52 to assume the position seen in Fig. 7. The intending purchaser or user now grasps one of the article removing devices 37 and moves it forwardly in the slot 17 and the article carrier rides up the inclined face or cam face 58 and in moving down the vertical portion of the slot 16, it rocks the lever 52, thereby causing the stop pin 57 to move upwardly and prevent the removal of more than one article at a time. The article carrier 37 moves the article into the compartment 22 as seen in Fig. 1 so that the article is now in a position accessible to the user. At the same time that the locking bar 42 moves longitudinally to move its end 51 out of the path of an article to be withdrawn, the stem of the

article to be withdrawn, the stem of the

valve 72 is received in the slot 62 of the lever 42 and as such portion of this lever 42 is now moving upwardly, it engages the abutment 73 and raises the valve 72, thus 5 permitting liquid soap to pass from the soap dispenser 70 into the measuring chamber 74.

The locking bar 42 moves forwardly and as soon as its aperture 63 registers with the abutment 73, the valve 72 is free to move 10 downwardly and close the port 71. The user now actuates the spring pressed valve 76 and the liquid soap passes from the chamber 74 into his hand. In case powdered soap or soap of a solid nature is employed, 15 the bar 42 rocks the lever 81 and actuates the slide valve 80 to permit the soap to pass to the measuring chamber 79. The intending user then actuates the spring pressed valve 74 so that the soap can pass into his hands 20 ready for use. The towels 35 which have been used slide down on the towel retainer 18 into the compartment 23 and are received on the tubular sleeve 30. The locking bar 42 is returned to its normally locked position 25 by the withdrawal of a towel from the compartment 5. After the locking bar 42 is moved forwardly the weighted end of the lever 61 is moved upwardly across the slot 16 so as to be in the path of an article 30 which is being removed. As this article is moved downwardly, it engages the weighted end of the lever 61, rocking it on its fulcrum and causing the bar 42 to be returned to its 35 locked position seen in Fig. 11. If all the towels have been removed from the machine, the bar 85 will move downwardly and bear against the lever 86, thus causing one end thereof to move upwardly and close the coin slot 39 and thus render the machine inoperative. 40 The used towels which have been assembled on the tubular sleeve 30 are removed with the sleeve 30 and sent to the laundry and another sleeve 30 is secured in place ready to receive the used towels.

45 The construction of the coin chute 40 is such that if a check or coin is retained therein, the lever 64 will open the movable side of the coin chute and cause such improper or bogus coin to pass by means of the guide 50 65 to the pocket 66 in a position accessible to the intending purchaser.

In accordance with my present invention, the articles to be dispensed are supported at the upper portion of the cabinet and are 55 then moved laterally and then downwardly into a position accessible to the intending user. After they are used, they pass into a compartment provided for their reception. The towel retainer is carried by one of the 60 doors so that when the door is opened, the towels may be readily assembled with respect to the container or removed therefrom. The coin controlling mechanism and the soap dispensing mechanism are carried by 65 the other door so that when such door is

opened, such mechanisms are readily accessible for purposes of inspection, cleaning or repairs.

In accordance with my present invention, the articles or material to be dispensed can 70 not be obtained without depositing in the machine a check or coin of the proper denomination and one is able to simultaneously dispense or vend two different articles, such as for example, a towel and a predetermined 75 amount of soap.

It will now be apparent that I have devised a novel and useful dispensing cabinet which embodies the features of advantage enumerated as desirable in the statement of the invention and the above description, and while I have, in the present instance, shown and described typical embodiments of it which will give in practice satisfactory and reliable results, it is to be understood that 85 these embodiments are susceptible of modification in various particulars without departing from the spirit or scope of the invention or sacrificing any of its advantages.

Having thus described my invention, what 90 I claim as new and desire to secure by Letters Patent, is:—

1. In a device of the character stated, a casing, an article guide within said casing adapted to guide an article into a position 95 accessible to the intending user, an article removing member slidably on said guide, locking mechanism for said articles, means actuated by an article removing member to effect the relocking of said locking mechanism, and mechanism independent of said means to prevent more than one article at a time being removed from said casing.

2. The combination with a towel cabinet, of a towel retainer within said cabinet, a 1 towel receiving sleeve removably carried by said retainer, a stop at one end of said sleeve, a bar connected with said stop and extending in proximity to the other end of said sleeve, and a second stop movably carried by said 1 bar.

3. The combination with a towel dispensing cabinet having a door, of a towel retainer detachably connected with said door, a sleeve carried by said retainer for the clean towels, and a sleeve carried by said retainer for the used towels.

4. The combination with a towel dispensing cabinet having a door, of a towel retainer detachably connected with said door, a sleeve carried by said retainer for the clean towels, a sleeve carried by said retainer for the used towels, and towel removing members slidably mounted on said retainer.

5. In a towel dispensing cabinet, a casing having a slot through one of its walls, a towel retainer in said casing, towel removing members extending through said slot and slidably mounted on said retainer, a lever movably mounted and extending into said

slot, locking mechanism for said lever and means actuated by said lever and independent of said locking mechanism to prevent more than one towel being removed at a time.

6. In a dispensing cabinet, a casing having a slot through one of its walls, an article retainer in said casing, a lever extending into said slot, article removing members 10 slidable in said slot and in the path of which said lever is located, locking mechanism, and a stop member independent of said locking mechanism and actuated by said lever due to the engagement of an article removing 15 member with said lever.

7. In a dispensing cabinet, a casing having a slot through one of its walls, an article retainer within said casing, article removing members slidable in said slot, a lever pivotally supported, a tension device for said lever to cause a portion of it to extend into 20 said slot in the path of an article removing member, locking mechanism for said lever, and a stop member independent of said locking 25 mechanism and actuated by said lever as an article removing member passes over said lever.

8. In a dispensing cabinet, a casing having a slot through one of its walls, an article 30 retainer within said casing, article removing members slidable in said slot, a lever pivotally supported and having an inclined face in the path of an article removing member, a tension device for said lever to cause a 35 portion of it to extend into said slot, and a stop pin located in proximity to said inclined face and actuated by said lever to prevent more than one article being removed at a time.

9. In a dispensing cabinet, a casing having a slot through one of its walls, an article retainer within said casing, a lever pivotally supported, a tension device to cause said lever to extend into said slot, article removing 5 members slidable in said slot, a stop member actuated by said lever to prevent more than one article being removed at a time, locking mechanism for said lever and said stop member, and means to effect the 10 unlocking of said locking mechanism.

10. In a dispensing cabinet, a casing having a slot through one of its walls, an article retainer within said casing, a lever pivotally supported, a tension device to cause said 5 lever to extend into said slot, article removing members slidable in said slot, a stop member actuated by said lever to prevent more than one article being removed at a time, locking mechanism for said lever and said stop member, means to effect the unlocking of said locking mechanism, and means actuated by an article removing mem-

ber to effect the relocking of said locking mechanism.

11. In a dispensing cabinet, a casing having a plurality of doors contributing to form a slot and provided with an open compartment communicating with said slot, an article retainer within said casing communicating with said compartment and 65 carried by one of said doors, article removing members slidable in said slot, locking mechanism carried by the other of said doors, means to effect the unlocking of said mechanism, and means controlled by an 70 article removing member to effect the relocking of said mechanism.

12. In a device of the character stated, a cabinet having a slot in one of its walls, an article retainer for said cabinet, article removing members mounted in said slot to effect the removal of the articles into a position accessible to the user, a lever pivotally mounted and in the path of an article removing member to be depressed thereby, and 80 a stop operatively connected with said lever and positioned to move into said slot when the lever is depressed to prevent the removal of the other articles on said article retainer.

13. In a device of the character stated, a 90 cabinet having a slot in one of its walls, article removing members guided in said slot, an article retainer in said cabinet, means in said slot and directly actuated by an article removing member to close said 95 slot, a second lever mounted to move into said slot to engage said lever, and means to release said second lever to permit the operation of said first lever.

14. In a device of the character stated, a 100 cabinet having a slot in one of its walls, an article retainer in said cabinet, article removing members in said slot, a lever pivotally mounted and having one end extending into said slot and provided with a cam 105 face in the path of an article removing member, and a stop pin positioned in proximity to said cam face and connected to said lever to be moved into said slot when said lever is depressed by an article removing 110 member.

15. In a device of the character stated, a cabinet having a slot, article removing means in said slot, a lever pivotally mounted and normally positioned in said slot, a tension 115 device for said lever, and a stop pin operatively connected to said lever and adapted to move into said slot when said lever is depressed by an article removing member.

JOHN FRITSCHE.
